APPARATUS FOR THE INTERMITTENT DELIVERY OF FLUIDS

Filed August 8, 1924

A. Reginald M. McCLean,
Inventor.

Reginald M. McCLean
Attorney.

Patented Sept. 14, 1926.

UNITED STATES PATENT OFFICE.

ALLISON REGINALD M. MACLEAN, OF MONTREAL, QUEBEC, CANADA.

APPARATUS FOR THE INTERMITTENT DELIVERY OF FLUIDS.

Application filed August 8, 1924. Serial No. 731,002.

My invention relates particularly to apparatus for the intermittent delivery of fluids in measured quantities and has for its object to provide an apparatus of this nature susceptible of operation by atmospheric pressure and thereby, when desired, be operable to deliver a liquid in intermittent quantities. A further object is to deliver by an apparatus of this nature measured quantities; and a still further object of the invention is to start a siphon included in and forming a part of the apparatus. Another object of the invention is to start a siphon by subjecting the discharged end thereof to suction induced by the condensation of a vapor.

To this end the invention, broadly stated, consists of an apparatus comprising a container for the fluid and having atmospheric communication, a discharge device, and a pipe connection between the container and discharge device, and the pipe connection having a valve controlling the same, and the discharge device having a discharge cock. In the preferred embodiment of my invention the communication between the container and the discharge device is in the form of a siphon and the discharge device is constructed and arranged to have a vapor condensed therein for the purpose of creating a suction whereby the siphon is started.

For full comprehension, however, of my invention reference must be had to the accompanying drawing in which my apparatus is illustrated diagrammatically.

The container in the apparatus illustrated is in the form of a flask A, the mouth of which is closed by a cork A¹ carrying a carbolic filter B in the form of a glass tube bent to a right angle, with one leg extending down through the cork into communication with the interior of the flask, its other leg being horizontal with diminished mouth B¹ and containing absorbent cotton impregnated with carbolic acid. The siphon consists of a tube bent to present continuous legs 2, 3 and 4 extending at right angles to each other, the leg 2 passing downwardly through the cork to within close proximity of the bottom of the flask, the leg 3 extending horizontally and the leg 4 depending to a point below the bottom of the flask. A discharge device preferably in the form of a burette F is located at a lower level than the bottom of the tube 4 and its air intake is connected

by a rubber tube G to a carbolic filter H similar to the filter B. Near the lower end of the burette is a nipple F¹ while the lower extremity is bent at right angles and carries a nozzle and stop cock K. The nipple F¹ is connected to the lower end of the leg 4 of the siphon by a length of rubber tubing, the passage through which is controlled by a screw clip E or other suitable valve.

The burette is preferably graduated in cubic centimeters or other volume divisions as required.

Operation.

70

The container is first filled with the fluid to be delivered intermittently. Then the tube D is detached from tube 4 the stop cock K is closed and the burette is charged with a condensable vapor through the tube D. It is necessary that the temperature of the vapor be sufficiently higher than atmospheric to cause a suction on cooling in the closest apparatus. The valve or clip E must be left open during this operation, thus permitting the condensable vapor to find its way to and escape from the filter H. The tube D is reconnected to tube 4. The stop cock is then opened which permits the condensed or partially condensed fluid in it to run out of the burette. The stop cock K is then closed and the tube G pinched, which causes the partial vacuum created by the condensation of the vapor in the burette to draw on the tube D and start the siphon. As soon as the fluid from the container appears in the burette the valve or clip E is then closed and the tube G is released. The siphon is now complete and the apparatus ready for use.

I prefer to employ steam in the operation of my apparatus. The steam enters the burette and finds its way to the filter H as above described. I do not confine myself to steam as other condensable vapors may be employed. Nor do I confine myself to the use of a flask or burette because any suitable container and discharge device may be used with the tubing I have shown, or other suitable means of communication between the discharge device and the siphon, without departing from the spirit of my invention. The invention is also applicable to the measuring and transferring of obnoxious and poisonous fluids; and to large operations where tanks and other engineering equipment is used, within the scope of my invention. The

method of starting a siphon by the condensation of a vapor is an essential part of the invention.

What I claim is as follows:

- 5 1. The method of starting a siphon consisting in subjecting the discharge end of the siphon to a suction produced by the condensation of a vapor.
- 10 2. In the intermittent delivery of fluids the combination with a container having atmospheric communication, of a discharge device having atmospheric communication, a

tube effecting communication between the container and discharge device, a valve controlling the tube, and a discharge cock on the discharge device, the said tubes and container and discharge device being in siphonic relation, and means whereby the portion of the apparatus below and in communication with the siphon may be steamed, for the purpose set forth.

In testimony whereof I have signed my name to this specification.

A. REGINALD M. MACLEAN.
